(57) **CLAIM**

The ornamental design for a chair, as shown and described.

DESCRIPTION

FIG. 1 is a top, front, right side perspective view of a chair, showing our new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of a portion labelled 9 in FIG. 1. The broken lines in the drawings depict portions of the chair that form no part of the claimed design.

The dash dot dash lines in FIG. 1 and FIG. 9 are for the purpose of depicting the cut line of the enlarged view and no part of the claim.
